UNITED STATES PATENT OFFICE.

SAMUEL STRASBURGER, OF BOSTON, MASSACHUSETTS.

DESIGN FOR WATCH-CASES.

Specification forming part of Design No. 7,773, dated September 22, 1874; application filed April 23, 1874.
[Term of Patent 7 years.]

CASE B.

To all whom it may concern :

Be it known that I, SAMUEL STRASBURGER, of Boston, in the county of Suffolk and State of Massachusetts, have invented a Design for Ornamenting Watch-Cases, of which the following is a specification:

Figure 1 is a front view of my ornamental watch-case, the reverse being the same.

In the drawing, which fully represents the nature of my design, and which is more especially adapted to watch-cases having rounded lids, A is the central portion of the lid, and B the border. The part A is engine-turned, or ornamented with lathe-work, and has a shield-shaped center, nearly plain, as shown. The border B is ornamented with fine lines or scroll-work; but prominent in the ornamentation of the same are a series of "horn-of-plenty" or "thousand-leaves" scrolls, extending entirely around the portion A, said scroll reaching from the part A to the outer edge of the lid, the edge or part *a a a* between the lids being beaded or knurled, as shown.

I prefer to ornament the part A of the case with lathe-work, and to use a shield in the center, as described; but these may be changed without departing from the spirit of my invention, not being in themselves claimed by me, the distinctive character of my design being the ornamental border B and beaded edge *a a a*, combined and arranged with the engine-turned part A, as shown.

What I claim as my invention is—

A design for watch-cases, composed of the central ornament *b*, surrounded by the lathe-work A, a bordering of scroll-work, B, and a beaded edge, *a a a*, as described.

In testimony whereof I have hereunto subscribed my name this 20th day of April, 1874.

SAMUEL STRASBURGER.
